APPARATUS FOR PERFORATING WELL CASINGS BY MEANS OF SHAPED CHARGES

Marcel Schlumberger, Paris, France, assignor, by mesne assignments, to Borg-Warner Corporation, Chicago, Ill., a corporation of Illinois

Application November 23, 1949, Serial No. 128,950

Claims priority, application France January 22, 1949

1 Claim. (Cl. 102—20)

The present invention relates to shaped charge well casing perforating apparatus and more particularly to new and improved perforating apparatus of this character which incorporates a novel and highly effective assembly of shaped charges in a pressure-resistant container adapted to be lowered into a well.

Devices embodying so-called "shaped" or "hollow" charges have been employed heretofore for perforating well casings and the like. In one form of apparatus used previously for this purpose, a plurality of shaped charges are mounted in an elongated tubular support inserted in an elongated, enclosed pressure-resistant housing, the charges being disposed in substantial alignment with closed ports formed in the side wall of the housing. Apparatus of this type is not entirely satisfactory because the charge support tends to rotate with respect to the housing while the latter is being positioned in a well. This may cause mis-alignment between the charges and their housing ports, resulting in severe damage to the housing and partly or wholly ineffective perforating operations when the charges are detonated in a well.

It is an object of the invention, accordingly, to provide new and improved shaped charge well casing perforating apparatus in which the charges are fixedly secured in a pressure-resistant housing and are at all times maintained in accurate alignment with ports formed in the side wall of the housing.

Another object of the invention is to provide new and improved perforating apparatus of the above character which comprises a small number of parts that can be quickly and easily assembled.

A further object of the invention is to provide new and improved perforating apparatus of the above character which is designed to insure the formation of an explosive jet of maximum effectiveness.

These and other objects of the invention are attained by providing perforating apparatus comprising a hollow, elongated enclosed housing having ports therein adapted to be tightly closed by suitable cap means. Shaped charges with liners are mounted in containers which are adapted to be inserted through the ports. Means are provided on the inside wall of the housing opposite each of the ports for supporting the rear ends of the charge containers, and the forward ends of the latter are supported in the housing ports and are retained therein by the cap means. Each of the charge containers has an outwardly open slot at the rear end thereof to facilitate the placement of a detonating fuse at the time the containers are inserted in the housing. With this construction, assembly of the perforator can be accomplished quickly and easily and the charges are always maintained in accurate alignment with the ports in the housing.

The invention may be better understood from the following detailed description of a preferred embodiment thereof, taken in conjunction with the accompanying drawings, in which:

Fig. 1 is a view in longitudinal section of shaped charge

2

well casing perforating apparatus constructed according to the invention; and

Fig. 2 is a view in transverse section taken along line 2—2 of Fig. 1.

5 In the preferred form of the invention shown in Fig. 1, the perforating apparatus comprises a hollow, cylindrical pressure-resistant housing 10 closed at top and bottom by tightly fitting caps 11 and 12 and having a plurality of ports 13 formed in the side wall thereof. Preferably, the ports 13 are longitudinally spaced apart along the housing 10 and angularly disposed about the longitudinal axis thereof, and they are closed by conventional threaded or plug-in caps 14, gaskets or washers 15 being provided to insure tightness. The housing 10 may be secured to a supporting cable 27 by means of which it may be positioned in a cased well (not shown).

Mounted in the housing 10 are a plurality of shaped charge assemblies 16 each comprising a container 17, a shaped explosive charge 18 and a liner 19, preferably of metal. The charge assemblies 16 are preferably designed according to the disclosure in copending application of Andre Blanchard, Serial No. 123,003, filed October 22, 1949, for "Shaped Charge Perforating Apparatus," so that undirected forces developed upon detonation will be relatively reduced. Thus, each charge is mounted in a pressure-resistant container 17 made of a suitable dense material such as lead or a plastic compound containing a filler, for example; the inner wall portion of the container 17 which surrounds the liner 19 converges rearwardly; and the apex angle of the liner 19 is greater than the apex angle of the charge receiving chamber in the container 17, these angles preferably being 55° and 30°, respectively.

According to the invention, each container 17 is provided with a cylindrical forward portion 20 extending beyond the liner 19 and the charge 18, which forward portion 20 is adapted to be closely fitted in one of the ports 13. Also, each container has a rear portion 21 which may be seated in a recess 22 formed in the interior wall of the housing 10 opposite a port 13. The rear portion 21 and the recess 22 may be tapered as shown in Figs. 1 and 2 to facilitate entry of the former into the latter during the assembly operation as described below. Each container 17 is retained in position by the cap 14 fitted in the corresponding port 13.

In order to facilitate the placement of a detonating fuse in operative relation to the explosive charges 18, each container 17 is provided with a rearwardly open slot 23 communicating with a tubular passage 24 within which 50 a Primacord fuse 25 is adapted to be inserted. The fuse 25, when in position, is preferably separated from the explosive charge 18 by a relatively thin wall 26.

Detonation of the fuse 25 may be accomplished in any suitable manner from the surface of the earth. For 55 example, detonation may be effected by an electric blasting cap 28 ignited by a source of electrical energy 29 at the surface of the earth. One terminal of the source 29 may be grounded at 30, and its other terminal may be connected in series with a switch 31 and a conductor 60 32 in the cable 27 to the blasting cap 28, the circuit being completed through the ground.

To assemble the perforator, the cap 11 is removed and the blasting cap 28 and the Primacord fuse 25 are inserted in the housing 10. With the caps 14 removed, the charge 65 containers 17 are inserted through the ports 13 until they are properly supported in the recesses 22 and by the ports 13. During this operation, the Primacord fuse 25 passes through the slots 23 in the rear ends of the containers 17 to the tubular passages 24. The ports 13 are then closed by the caps 14 with the washers 15 in place to insure tightness, thus completing the assembly.

In operation, the housing is moved to a desired level in

a bore hole (not shown) by means of the cable 27 and the switch 31 is then closed. This sets off the blasting cap 28 and detonates the charges 18 simultaneously. The explosive jets thus formed pass through the caps 14 and penetrate the adjacent well casing. Since the charge assemblies 16 are maintained in accurate alignment with the ports 13, highly effective jet formation is achieved without material damage to the housing 10 by the explosive jets. Further, since the charge assemblies 16 are designed according to the disclosure in the aforementioned copending application Serial No. 123,003, undirected forces developed around the charges upon detonation thereof are substantially reduced, so that no appreciable deformation of the housing 10 occurs.

For effective jet formation, it is important that symmetry of the charge, its liner, and the charge receiving opening in the container be accurately maintained. It has been found that even threads formed on the outside of the container may disturb the symmetry of the assembly to such an extent as to affect adversely the formation of the jet. For this reason, it is preferable to use only partial threads wherever threads are employed to secure parts together as in the case of the caps 14. Preferably, conventional plug-in caps should be used instead of screw-in caps for this purpose.

The invention thus provides a novel and highly effective shaped charge apparatus for perforating well casings or the like. By virtue of the construction described above, assembly of the perforator can be accomplished simply and quickly, and accurate alignment between the shaped charge assemblies and the housing ports is maintained at all times.

The specific embodiment described above is intended to be merely illustrative and it is obviously susceptible of modification within the spirit of the invention. That embodiment, therefore, is not to be regarded as limiting in any way the scope of the following claim.

I claim:

In well casing perforating apparatus, the combination of an enclosed, hollow, pressure-resistant housing adapted to be lowered into a well and having at least one port

formed in the side wall thereof, means forming a recess in the inner wall of said housing opposite said port, an explosive charge container so constructed and arranged that it can be inserted into the housing through said port and positioned with a forward portion thereof snugly fitted in said port and a rear portion thereof seated in said recess, closure means for the port and for fixedly retaining said charge container in assembled position in the housing, means forming a substantially conical chamber in said container diverging to a coaxial, substantially cylindrical opening facing said port, means forming a longitudinally extending passage near the apex of said conical chamber and separated therefrom by a relatively thin wall, means forming a rearwardly and sidewardly open longitudinal slot at the rear end of said container and communicating with said passage to facilitate placement of detonator means in said passage, detonator means disposed within the housing and mounted in said passage, an explosive charge in said conical chamber and having a hollowed-out portion facing said port, a liner fitted to said hollowed-out portion, and means for firing said detonator means from the surface of the earth.
